UNITED STATES PATENT OFFICE.

LEWIS L. SCOTT, OF ST. LOUIS, MISSOURI.

OIL BURNER.

Application filed March 20, 1926. Serial No. 96,290.

This invention relates to oil burners as used for heating homes.

The object of my invention is to provide a simple and effective means of igniting and burning heavy oil, without the formation of carbon on the fuel nozzle or ignition device or on the walls of the combustion chamber, or the surfaces of the furnace, which it is adapted to heat.

10 Another object of my invention is to provide a protector plate near the tip of the flame director to protect said flame director tip from the intense heat in the furnace, said protector plate to be made of a metal that 15 will not be readily destroyed by high temperatures.

I have found that it is a very difficult matter to burn heavy oil without the formation of carbon, either around the burner nozzle 20 and ignition device, or on the walls of the combustion chamber, even when combustion is apparently clean and there is no smoke or odor from the burning oil. It is highly desirable to not only avoid all carbon formation, 25 but to be able to burn heavy oil in a small combustion chamber.

The burner head shown in my present application was evolved after hundreds of experiments were carried on, and it has been 30 tested with oils ranging from 40 gravity to 27 gravity. Tests on this burner head show that it will burn all grades of oil cleanly and without carbon formation, and the flame is very compact, thereby permitting its 35 use in a small combustion chamber. If the fire is not compact and combustion is not completed in a small space, then there will be carbon formation on the walls of small combustion chambers in small furnaces, and 40 the carbon will build up and cause very undesirable results. I have tested many variations of this combustion head and have been able, in most of them, to get good clean combustion and a clean condition around the 45 nozzle and spark wires, but there would be an unbalanced condition in the flame, and where it would touch the combustion chamber, carbon would form. If a change were made, in the attempt to balance the flame, then there was usually a bad condition 50 around the nozzle and spark wires. The main point of difference between my present invention and my application No. 51,979, is that the spark wires are carried by a part 55 that is necessary for proper air distribution

and there is no interference caused by a support for the spark plugs. In some cases, I also provide a small air plate, which plate assists in blowing the vapors and flame away from the nozzle and spark wires.

60 In the accompanying drawing:—

Figure 1 is a top view of my burner assembly, (shown partly in section and with electric ignition removed), showing a diagram of the electric wiring.

65 Figure 2 is an enlarged sectional view of a modification of my burner head.

Fig. 3 is a front view of burner shown in Figure 2.

70 Figure 4 is a back end view of Figure 2, shown in reduced size and with oil diaphragm removed.

75 Referring now to the drawing, the numeral 1 indicates an electric motor which operates a blower wheel 2 and an oil pump 3. The numeral 4 is a suction pipe running from pump 3 to an oil tank, not shown. 5 is the discharge from pump 3, which runs to casting 6, which casting connects to fuel spray nozzle 7. The pump 3 is adapted to 80 force liquid fuel through nozzle 7, at from 20 to 100 pounds pressure, so that fuel will be sprayed into a very fine fog-like mist. 8 is an air receiver which is connected to the blower casting 9 by the air pipe 10. By 85 referring to Figure 4, it will be seen that the air receiver 8 is in the form of an involute curve and is adapted to rotate the air, which rotating air will pass into the outer flame director 11. The numeral 12 is a conical tip 90 placed on the end of outer air director. The numeral 12^a indicates a protector plate, (see Figure 1), which is secured in spaced relation to the conical tip 12. The numeral 13^a indicates an air space between the tip 12 and 95 the protector plate 12^a, said air space 13^a may be filled with asbestos. 13 indicates a section of a furnace into which the oil flame is projected. 14 indicates an inner air director which is supported by the nozzle extension 15, through the screws 16, which screws are threaded into the part 17 in a manner that permits said screws to tighten 100 against the nozzle extension 15. The numeral 18 indicates a circular disc, made of insulating material such as porcelain. The disc 18 is provided with six small air holes 19. The disc 18 is secured to the part 17 by the screws 20 and is adapted to carry the spark wires 21, which wires are secured to 110

disc 18 by the nuts, as clearly shown in Figure 2. The wires 22 and 23 connect to the spark wires and run to the insulating block 24, which block is carried by the air receiver head 25. The air receiver head 25 also carries the nozzle extension tube 15, which tube is held secure by the set screw 26. The numeral 27 indicates a small plate which helps to prevent the burning back of the flame around the nozzle and spark terminals. The plate 27 is shown in its true position in Figure 3. Said plate is shown approximately 90 degrees out of position in Figure 2.

15 I will now describe the electrical connections and control devices.

The numerals 28 and 29 indicate the main power wires. 29 runs directly to motor 1 and spark transformer 30. The wire 28 runs to motor 1 and spark transformer 30 through the relay switch 31. The high tension wires 32 and 33, of the transformer 30, run to the spark wires 34 and 35. The numeral 36 indicates a small transformer, which is connected to power wires 28 and 29, and which reduces the 110 volt circuit to about 15 volts. The numeral 37 indicates a room thermostat, which is usually placed in the living room of the house and controls the operation of the burner according to room temperature. The wire 38 runs from the transformer 36, through room thermostat 37, wire 39 and relay switch 40, and back to transformer 36, thereby completing the 15 volt circuit.

When the room temperature drops so as to close the contacts on room thermostat 37, the relay switch 40 will be energized, thereby closing the switch 31 and starting the motor 1 and spark transformer 30. Fuel will be sprayed out of the nozzle 7 and air will be forced from the blower through the pipe 10 into the air receiver 8 and will be caused to take a rotating motion by said air receiver, and will flow to the fuel spray through air directors 11 and 14. The electric spark, at the terminals of the spark plug, will ignite the fuel and the oil flame will burn in the combustion chamber 41. 50 Due to the distribution of air through the air directors 11 and 14, and due to the plate 27, there will be no flame around the nozzle and spark wires—the burning of oil will start on about the line 42 of the tip 12. 55 Due to the lack of air interferences and to the mixing of air with the fuel spray, complete combustion will take place in the chamber 41, (which chamber may be 15 inches in diameter), without the flame touching the combustion chamber. There will be no carbon deposits in the combustion chamber or around the nozzle or spark wires.

I claim:—

1. In an oil burning device of the class described, in combination with a spray nozzle and means for supplying fuel thereto under pressure and thereby mechanically spraying said fuel, means for igniting the fuel, means for furnishing air at low pressure to the fuel spray to promote combustion, a mixing cone for causing the air to be mixed with the fuel spray, a disc located back of the fuel nozzle and in the path of the air going to the fuel spray, said ignition means being supported by said disc, an air receiver which receives air from the air supply means and which causes said air to rapidly rotate, said air receiver having a projecting casting, said casting having its outlet formed with a reduced cone-like diameter, in which is enclosed said fuel nozzle, ignition means, mixing cone and disc, said casting having no other parts back of the fuel nozzle to disturb the air currents in said casting.

2. In an oil burning device of the class described, in combination with a spray nozzle and means for supplying fuel thereto, means for igniting said fuel, means for furnishing air to the fuel spray to promote combustion, a disc located back of the fuel spray nozzle and in the path of the air going to the fuel spray, said disc serving to support the ignition device, a pipe for conducting fuel to said spray nozzle, a funnel located in the path of the air and having its large outlet pointed towards the air supply means and its small outlet directed towards the fuel spray, said fuel pipe running to said nozzle serving as a support for said disc and said funnel, an air receiving casting for receiving air from the air supply means, said air receiving casting enclosing the fuel nozzle disc and cone and said air receiving casting having a cone-like outlet of reduced diameter.

3. In an oil burning device of the class described, in combination with a spray nozzle and means for supplying fuel thereto, means for igniting the fuel, means for furnishing air to the fuel spray to promote combustion, a disc made of insulating material, located back of the fuel spray nozzle and in the path of the air going to the fuel spray, said disc serving to support the ignition device, a pipe for conducting fuel to the spray nozzle, a funnel-shaped casting, located in the path of the air and having its large outlet pointed toward the air supply means and its small outlet directed toward the fuel spray, said fuel pipe running to said fuel nozzle serving as a support for said disc and said funnel, an air receiving casting for receiving air from the air supply means, said air receiving casting enclosing the fuel nozzle disc and cone and said air receiving casting having a cone-like outlet of reduced diameter.

4. In an oil burning device of the class described in combination with a spray nozzle

- and means for supplying fuel thereto, means for igniting the fuel, means for furnishing air to the fuel spray to promote combustion, a circular disc located back of the fuel nozzle and in the path of the air going to the fuel spray, said disc serving to produce eddy-currents of air and cause intimate mixing of the air and fuel spray, a funnel-shaped casting located in the path of the air on the lee side of said circular disc and having its large diameter directed toward the air supply means and its small central outlet directed toward the fuel spray, the large end of said funnel-shaped casting being of greater diameter than the circular disc, an air receiving member for receiving air from the air supply means, said air receiving member enclosing the fuel nozzle, disc and cone and having a cone-like outlet, said spray nozzle being located near the cone-like outlet so that neither the fuel spray or the burning oil flame will contact with the wall of said outlet.
5. In an oil burning device of the class described in combination with a spray nozzle and means for supplying fuel thereto, means for igniting the fuel, means for furnishing air to the fuel spray to promote combustion, a circular disc located back of the fuel nozzle and in the path of the air going to the fuel spray, said disc serving to produce eddy-currents of air and cause intimate mixing of the air and fuel spray, a funnel-shaped casting located in the path of the air on the lee side of said circular disc and having its large diameter directed toward the air supply means and its small central outlet directed toward the fuel spray, said spray nozzle being located near the outlet of the funnel-shaped casting so that neither the fuel spray or the burning oil flame will contact with the wall of said outlet. 25 30 35 40

In testimony whereof, I have hereunto set my hand.

LEWIS L. SCOTT.
